UNITED STATES PATENT OFFICE.

MORLEY PUNSHON REYNOLDS, OF CLEVELAND HEIGHTS, OHIO, ASSIGNOR TO THE
W. S. TYLER COMPANY, OF CLEVELAND, OHIO, A CORPORATION OF OHIO.

SCREENING APPARATUS.

Application filed September 3, 1920, Serial No. 408,001. Renewed December 11, 1924.

To all whom it may concern:

Be it known that I, MORLEY PUNSHON REYNOLDS, a citizen of the United States, and a resident of Cleveland Heights, county 5 of Cuyahoga, and State of Ohio, have invented a new and useful Improvement in Screening Apparatus, of which the following is a specification, the principle of the invention being herein explained, and the best 10 mode in which I have contemplated applying that principle so as to distinguish it from other inventions.

The present improvements, relating, as indicated, to screening apparatus, are more 15 particularly directed to an improved machine for separating and classifying materials in which a more effective vibration, and consequently a more accurate separation and longer screen life are secured. To the 20 accomplishment of the foregoing and related ends, said invention, then, consists of the means hereinafter fully described and particularly pointed out in the claims.

The annexed drawing and the following 25 description set forth in detail certain mechanism embodying the invention, such disclosed means constituting, however, but one of the various mechanical forms in which the principle of the invention may be used.

30 In said annexed drawing:—

Fig. 1 is a longitudinal vertical section through an inclined screening machine, in which my invention is embodied; Fig. 2 is a plan view of a woven wire screen and mounting therefor; Fig. 3 is a transverse section through one side of such screen and mounting; Fig. 4 is an enlarged plan view of the screen alone; and Fig. 5 is a chart showing diagrammatically the relative hardness of the wires in my screen.

The inclined screening apparatus at present in most general use consists of an inclined framework in which a woven wire screen is mounted, also in an inclined position, with its inclined or longitudinally extending edges attached to the frame and its upper and lower (transverse) edges free. The screen has usually been vibrated by mechanical means, although electrical means 45 are now sometimes employed, and this construction has practically become standard. A machine, such as described, is capable of very much more effective vibration than the earlier types in which the screen was fas-

tened along all edges to a frame and then 55 vibrated or shaken.

My invention is here illustrated and described in connection with an inclined screening machine.

In Fig. 1, I have shown an inclined screen 1, (frame not shown), consisting of a supporting frame 2 mounted in an inclined position with its upper end resting upon supports 3. The framework upon which the woven wire screen is mounted consists 60 of two parallel longitudinal frame members 4 which are connected by end members 7, which merely rest upon the longitudinal members and do not prevent their being moved toward or away from each other for the purpose of tensioning or loosening the screen. The screen 8 has its edges 9 rebent upon themselves and fastened in a hook-like grip by means of what is usually termed a hookstrip 10, which is provided with a 65 flange 11, adapted to engage over the edges of the longitudinal frame members. Of course other means for uniformly fastening the screens may be employed. These longitudinal frame members are connected by 70 means of tension rods 12, of which there are usually three or four in the ordinary screen frame, which have right and left-hand threaded adjustment in sockets 13, 75 carried on the two frame members. 80

Mounted above the screen 8 is a vibrating device which is usually carried upon the casing surrounding and enclosing the screen. This vibrating device consists of an electromagnet 14, operating an armature 15, which 85 is attached directly to the screen edge by means of a U-shaped bridge 16 and a resilient vibrating strip 17, the latter being disposed longitudinally and centrally along the screen. The action of this vibrating apparatus is to pull up the armature, carrying the screen with it, and then jarring the same at the upper limit of the armature's movement. This jar is transmitted to all 90 portions of the screen surface through the bridge 16 and the resilient strip 17. The result of this action is to vibrate the screen surface between its lateral edges, and it must be remembered that the top and bottom edges of the screen surfaces are 95 entirely free. It is therefore the wires which extend transversely of the inclined screen 100 which are in vibration, the longitudinal 105

wires being vibrated to a very much less degree than the transverse wires.

In Figs. 2 and 4, I have shown the screen 8. In Fig. 2 the screen 8 is shown as it is formed ready for application to a screening machine, and having the hook strips 10 secured to either longitudinal edge and the resilient vibrating strips 17 secured centrally along the screen.

In Fig. 4, I have shown an enlarged plan view of a woven wire screen consisting of the longitudinally extending wires 18 and the transversely extending wires 19. My invention is based upon an analysis of the vibratory action of a woven wire screen when mounted as previously described in an inclined screen frame under the action of a vibrating device of the type described. I have found that a very much more effective vibration can be secured in such a machine if the transverse wires, which are under a uniform vibratory tension, are formed of a hard, highly resilient wire. It is immaterial as to whether the longitudinal wires, which are not in tension, and which are not vibrated to any great extent, are formed of resilient or non-resilient wire, and any suitable weaving wire may be used for this purpose. The screen may be woven in any of the usual ways, so long as when applied to the inclined frame it has hard highly resilient transverse wires.

The resiliency and degree of hardness of the transverse wires is essential to secure the most effective vibration of the screen, but on the other hand there is another limit to the hardness of these wires which cannot be exceeded without being destructive to the wire screen. It will be seen, therefore, that any hard, highly resilient wire will not satisfy the requirements of such a machine as the degree of hardness of these wires must be confined between certain definite limits. In order to accurately define the limits of hardness and resiliency between which the hard wires must range to be effective in such a screen I have shown in Fig. 5 a chart, in which there is given diagrammatically the limits referred to. In this chart the diameter of the wire has been plotted vertically and the hardness readings have been plotted horizontally. These hardness readings have been made on a Rockwell hardness testing machine, which is a machine having an indenting device actuated by a given load to indent metal articles, after which the depth of the indentation is measured, and is translated into a number indicating the hardness of the particular specimens tested.

On the chart I have shown first a curve A marked "soft annealed" which is drawn from a large number of determinations on the Rockwell machine of the hardness of different samples of soft annealed wire of

various diameters. I have also shown two curves marked "B" and "C", of which the curve "B" was made from a large number of determinations on a Rockwell machine of the hardness of the softest specimens of wire which could be used in my improved screen and still secure the vibration that is desired. The curve marked "C" was similarly drawn after plotting the relative hardness readings on a Rockwell machine of a large number of specimens of wire which had the highest degree of hardness that would permit them to be used to secure the desired results in the present machine. Any wire whose hardness is between the limits indicated by the curves "C" and "B" is of the proper hardness for the transverse wires of my improved machine. Thus, for example, if a specimen of wire having a diameter of nine-hundredths of an inch were to be tested to determine its hardness, and hence, whether it could be used in the present machine, if its hardness lay anywhere between 26 and 51 on the Rockwell machine it could be used. Above and below these two limits the wire would be either too hard or too soft.

To state the condition and character of the hard resilient wires in another way I have determined the tensile strength of a large number of samples of wire which may be used for the hard highly resilient transverse wires in my machine. In the following columns I have given, first, the diameter of the wire in inches; in the second column, the limits of tensile strength between which the breaking strength of the wire must fall if it may be used as the hard transverse wire, and in the third column, the actual breaking strengths of soft annealed wire of various diameters.

Tension required to break wires.

[Pounds.]

Hard wire		Soft annealed (actual).
Diameter (inches).	Limits.	
.162	4000-2100	1400
.148	3400-1580	1200
.135	2600-1400	1050
.120	2100-1125	775
.105	2000-1020	615
.092	1600-790	460
.080	1100-570	375
.072	800-435	285
.063	550-300	205
.054	350-210	180
.047	250-140	127
.041	240-125	92
.035	175-90	68
.032	150-75	53
.028	120-65	42
.025	110-60	36
.028	100-50	29
.020	80-40	20
.018	65-25	11

13

It is well known that the tensile strength of wire varies directly as the hardness, and that a hard wire has a considerably higher

tensile strength than a soft annealed wire of the same size and material. Thus, in the tables given above, soft annealed wire having a diameter of ninety-two thousandths of an inch has an actual breaking strength of 460 pounds. Hard wires of the same diameter, and of a hardness sufficient to permit these wires to be used as the hard transverse wires in my machine, have a tensile strength falling between 790 and 1600 pounds. That is, the lowest limit which is permissible for the tensile strength of the hard wire is almost twice the tensile strength of a soft annealed wire of the same diameter.

Because of the extreme hardness of the wires which are tensioned in the present screen, it is essential that the edge portions of these wires be softened enough to permit of the continued vibration and bending back and forth of these wires which is experienced in the action of the screening apparatus. After the screen has been woven and before it is applied to the hook-strips or otherwise fastened to the frame, the two transverse edges are annealed or softened until the condition of the wires at the edges is in a soft annealed condition. In this way the edges of the hardened wire are secured in the body of the screen without the disadvantage of the early breakage of the wires at their point of attachment to the screen frame.

In my machine described above, it has been found that a remarkable change in the character of the vibration is effected, with the result that the machine has a considerably increased capacity. A screen provided with highly resilient transverse wires, maintained under a uniform, vibratory tension, can be vibrated very much more freely under the same intensity of impulses than screens otherwise mounted, and the screen

is "livelier" and shows very much less tendency to clog or "blind" when working on difficult materials.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In screening apparatus, the combination of an inclined screen-receiving frame, a woven wire screen mounted in said frame, said frame being provided with means tensioning all of the transverse wires of said screen to a uniform vibratory tension, said screen having hard resilient transverse wires, and means adapted to vibrate said screen.

2. In screening apparatus, the combination of an inclined screen-receiving frame, a woven wire screen mounted in said frame, said screen being provided with hard resilient transversely extending wires, means on said frame adapted to engage all of said transverse wires and tension the same to a uniform vibratory tension, and means adapted to vibrate said screen.

3. In screening apparatus, the combination of an inclined screen-receiving frame, a woven wire screen mounted in said frame, said screen being provided with hard resilient transversely extending wires engaged at their ends by said frame and maintained at a uniform vibratory tension, and the longitudinal wires of said screen being free, and means adapted to vibrate said screen.

Signed by me, this 26th day of August, 1920.

MORLEY PUNSHON REYNOLDS.
